PORTABLE PULPIT

Lloyd Walker, Lacon, Ill.

Application September 29, 1955, Serial No. 38,157

Term of patent 3½ years

(Cl. D33—14)

FIG. 2

FIG. 1

I claim:

The ornamental design for a portable pulpit, as shown.
